MILK BOTTLE CARRIER

Filed April 26, 1928

RUSSELL C. STOKES,
Inventor.

By *newright*.
Attorney.

UNITED STATES PATENT OFFICE.

RUSSELL C. STOKES, OF PORTLAND, OREGON.

MILK-BOTTLE CARRIER.

Application filed April 26, 1928. Serial No. 273,003.

My invention relates to apparatus for carrying bottles as a class.

The object of my invention is to provide a device which is simple, effective and positive in its action, either when applied or when released, and which will be locked when in a position for carrying.

The invention further provides a device which can positively be operated with ease 10 with one hand.

I achieve these objects, as well as other advantages, by the construction, combination and arrangement of parts illustrated in the accompanying drawings which form a part 15 hereof.

Like parts are represented by like characters in the various figures of the drawings.

Fig. I is a front elevation of the device in 20 secured position on a milk bottle.

Fig. II is a side elevation of Fig. I.

Fig. III is a front elevation of the device just ready either to be applied or to be taken off.

Fig. IV is a side elevation of Fig. III.

The device itself is predominantly of heavy wire construction and consists mainly of four connected parts arranged as follows:—

1st, a vertical bail member 1 having its lower ends integrally connected by an upwardly extending half-collar 2;

2d, a co-operating half-collar 3, hingedly connected at the lower end of the bail, and constituting, with the former half-collar, a gripping means;

3d, a vertically slideable operating means 4 having a pair of depending fingers 5 terminating with eyes 6; these eyes encompassing and acting upon the upstanding portions of the gripping half-collars 2 and 3;

4th, the handle member 7 engaging the free ends of the bail.

The operating means 4 has at its upper 45 middle portion a depending inverted T-shaped portion 8, to press down upon when opening the device for application to the neck of a bottle, or when releasing after use as a carrier. It will be noted that the ver-

tical portions of the bail 1 have kinks at 50 9; these are for purposes of locking the operating means in the upper position. It will be further noted that there are horizontal kinks 10 in the half-collar 3; these are for the purpose of making a positive and complete separation of the two half-collars 2 and 3.

Now as to operation: When it is desired to place the carrier on a bottle it is necessary only to press on the portion 8 of the 60 operating means 4 and open to a position as shown in Fig. III, and then by placing device over top of bottle, grasping said part 4 and drawing toward the handle 7, the gripping members 2 and 3 will close on the neck 65 of the bottle and be locked. When it is desired to remove the carrier, simply press down on member 8 and then lift the device. While the carrier is intended primarily for milk bottles, it is obvious that it can be used 70 for other bottles of similar type.

Having thus described my invention, what I claim as new is:—

In a bottle carrier the combination of: a longitudinal bail member integrally terminating in reversely extending legs with a half-collar thereon, a co-operating half-collar having legs hingedly connected at one end of the bail and comprising with the other half-collar a gripping means, longitudinally 75 slideable operating means having a pair of depending fingers terminating with eyes, the eyes surrounding and being slideable upon the legs of both collars, said means being positioned to allow it to press the cooperating 80 collar outwardly and to draw it inwardly to release or close the collar grips, an integral handle portion, kinks in the bail to engage the operating means when next to the handle, and transverse kinks in the co-operating 85 half-collar positioned to allow them to force the said half-collar outwardly when the operating means is pressed away from the handle, and to draw said collar to its gripping 90 position when the means is moved toward the handle.

RUSSELL C. STOKES.
